[57] CLAIM

The ornamental design for an antenna element, as shown.

DESCRIPTION

FIG. 1 is a front view in elevation of the antenna element of the present invention;

FIG. 2 is a rear view in elevation of the antenna element of FIG. 1;

FIG. 3 is a right side view in elevation of the antenna element of FIG. 1;

FIG. 4 is a left side view in elevation of the antenna element of FIG. 1;

FIG. 5 is a top plan view of the antenna element of FIG. 1; FIG. 6 is a bottom plan view of the antenna element of FIG. 1;

FIG. 7 is an enlarged view in elevation of the portion of the antenna element above the plane indicated by line 7—7 of FIG. 1;

FIG. 8 is an enlarged view in elevation of the portion of the antenna element between the planes indicated by lines 8—8 of FIG. 1;

FIG. 9 is an enlarged view in elevation of the portion of the antenna element below the plane indicated by line 9—9 of FIG. 1; and FIG. 10 is a perspective view of the antenna element of FIG. 1.
